UNITED STATES PATENT OFFICE.

EDWARD C. WILLIAMS, OF CHICAGO, ILLINOIS, ASSIGNOR TO EDWARD D. MOENG, OF CHICAGO, ILLINOIS.

APPARATUS FOR CLEANING ELECTROTYPE-CASTS AND TYPE-FORMS.

1,115,994.

Specification of Letters Patent.

Patented Nov. 3, 1914.

Application filed March 6, 1913. Serial No. 752,522.

To all whom it may concern:

Be it known that I, EDWARD C. WILLIAMS, a citizen of the United States, and resident of Chicago, county of Cook, and State of Illinois, have invented certain new and useful Improvements in Apparatus for Cleaning Electrotype-Casts and Type-Forms, of which the following is a specification, and which are illustrated in the accompanying drawings, forming a part thereof.

The invention relates to machines for cleaning electrotype casts and type forms; and its object is to provide a simple yet efficient and inexpensive device of this character.

The invention is fully hereinafter described, and is exemplified in the accompanying drawings, in which—

20 Figure 1 is a side elevation of the machine, some parts being broken away to show internal construction; Fig. 2 is a detail plan view thereof with a portion of the cover broken away; Fig. 3 is a vertical central section of the machine; and Fig. 4 is a detail plan section on the line 4—4 of Fig. 3.

The machine comprises a box-like casing 10, here shown as being square in form, mounted upon standards, as 11, 12, and being provided with a door 13 preferably hinged at its upper edge to the top 14 of the casing, the upper portion of the casing at the side at which the door is located being preferably cut back a short distance in 35 order that when the door is closed it may be inclined.

A shelf 15 projects from the side of the casing to which the door is applied, its upper face being upon a level with the bottom of the door opening in order that a plate, which may rest upon the shelf, may be pushed forward into the casing without interruption.

40 A revolving table 16 is located within the casing and is preferably square in form, its upper face being on the same level as the upper surface of the shelf 15. The table 16 is carried by a shaft 17, stepped in a suitable box 18 depending from the bottom 19 of the casing, the upper end of the shaft being 50 journaled in a box 20 carried by a spider 21 formed on the bottom of the casing.

A beveled gear 22 is mounted upon the shaft 17 immediately below the box 20, and meshes with a beveled pinion 23 carried by

a horizontal shaft 24 journaled in a box 25 mounted upon the bottom of the casing, and in a box 26 in one of its side walls. Upon the outer end of the shaft 24 there is mounted a pulley 27, driven by a belt 28 running over a pulley 29 carried by a shaft 30, upon which is mounted a gear wheel 31 meshing with a pinion 32 fixed upon the shaft of a motor 33. While I have shown an electric motor for driving the machine, which is carried by the frame of the machine, it is obvious that power may be applied to the pulley 27 from any other source.

A horizontal pipe 34 projects into the casing through one of its side walls and extends substantially to the opposite wall, and is located above the table 16. This pipe is provided with a longitudinal series of small apertures 35, which deliver obliquely downward, as indicated by the arrows appearing in Figs. 2 and 3. The pipe 34 is provided with a valve, as represented at 36, and is intended to deliver to the machine steam, water, or other fluid which it may be desired to use as the cleansing agent.

55 In order to provide for the drainage of fluid from the machine, the bottom of the casing 10 is preferably centrally apertured, as shown at 37, this aperture serving also to provide ample space for the gear 22 without increasing the depth of the casing. A funnel-shaped hood 38 is secured to the bottom of the casing 10, and incloses the aperture 37, and serves as a receptacle for receiving the cleansing fluid dripping from the table. 60 A drain faucet 39 is fixed in the hood 38 at its lower end and provides for the intermittent or constant drainage of the latter, as may be desired. The hood 38 also serves as a support for the shaft 17, the box 18 being 65 fixed within its lower end.

A plate is inserted into the casing by sliding it over the surface of the shelf 15 upon the table 16. The door 13 being now closed, power is applied to rotate the plate 100 at such speed as may be desired, and the cleansing fluid is turned on by opening the valve 36. The cleansing fluid is delivered upon the plate through the apertures 35, those located on one side of its center being 105 delivered upon it as it approaches, and those on the other side of the center being delivered upon the plate as it recedes. By this arrangement all sides of the upstanding characters are thoroughly cleansed. The 110

cleansing operation having been continued a sufficient length of time to thoroughly remove the ink or other substance which may be upon the plate, the motor is stopped and 5 the plate is removed in the same manner in which it was inserted, and may afterward be dried by any suitable means.

The revolution of the plate may be continued after the cleansing fluid has been cut 10 off, for the purpose of removing any liquid or other substance which may be upon the face of the plate, by centrifugal action.

While the pipe for delivering the cleansing fluid upon the plate is shown as entering 15 through one of the side walls of the casing, I do not desire to be limited to this arrangement, as the pipe may enter the casing at any convenient point. Neither do I desire to be limited to the precise arrangement or 20 form of the discharge orifices for delivering the cleansing fluid upon the plate. The invention is of sufficient scope to include any apparatus by which means are provided for discharging the cleansing fluid upon a plate 25 and causing the relative rotation in parallel planes of the plate and the pipe or nozzle from which the fluid is discharged.

I claim as my invention—

1. In a machine of the class described, in 30 combination, a casing having a centrally apertured dished floor plate and a lateral door, the bottom of the door opening being above the level of the margins of the floor plate, a depending funnel shaped hood having 35 its rim secured against the underside of the floor plate about the aperture thereof, a shaft stepped in the bottom of the hood,

and extending into the casing, a type supporting table fixed upon the upper end of the shaft and supported thereby at the level 40 of the bottom of the door opening, a drive shaft extending through the side wall of the casing below the level of the table, operative connection between the drive shaft and the first mentioned shaft and means for directing a cleansing fluid upon the table. 45

2. In a machine of the class described, in combination, a revolving type supporting table, a pipe for conveying a cleansing fluid extending over the table and having discharge orifices directed obliquely toward the table, the relative arrangement of the table and orifices being such that fluid is discharged from certain of the orifices in the direction of movement of that part of the 50 table upon which it falls and from other orifices against the direction of movement of that part of the table upon which it falls. 55

3. In a machine of the class described, in combination, a movable type supporting table, and means for directing streams of a cleansing fluid obliquely toward the table, the relative arrangement of the table and fluid directing means being such that the fluid flows in one of the streams in the direction of movement of that part of the table 60 upon which it falls and in another stream against the direction of movement of that part of the table upon which it falls. 65

EDWARD C. WILLIAMS.
